MOLDING MACHINE AND MOLD FOR THE
CENTRIFUGAL CASTING OF ANNULAR
BODIES

Walter Bremicker, Wuppertal-Barmen, Germany

Application October 6, 1936, Serial No. 104,265
In Germany January 17, 1936

3 Claims. (Cl. 22—65)

An application was filed in Germany on January 17, 1936.

The present invention relates to molding machines and molds for the centrifugal casting of annular bodies, and more particularly to the casting in this manner of thin annular plates of metal (brass, bronze, German silver and the like), which are intended to be cut into strips and then to be worked up into wire. In casting processes of this kind it is necessary, in the first place, to provide suitable molds which are rotatable about a horizontal axis and are made up of two detachable parts so as to render it possible to remove the casting after the setting of the molten metal which is introduced into the hollow space between the two parts of the mold. The introduction of the molten metal into the mold is effected in a manner known per se through the medium of an inlet member which is arranged in the cover of the mold and which is conically enlarged towards one end, but which must be constructed and mounted independently of the cover of the mold in order that it may be enabled to rotate at the same speed as the other parts of the mold or at a speed which is different therefrom. Besides this the inlet member is arranged in known manner so as to be longitudinally displaceable.

Some of the known molding machines have a rotating shaft journalled horizontally in the frame of the machine and molds arranged at the two ends of the shaft and each comprising a base portion and a cover, and are further provided with separately driven inlet members which are conically enlarged towards one end and are so located in openings provided in the covers of the molds as to leave in each case an annular space between the enlarged end of the inlet member and the cover of the mold of such width that the air heated by the entering molten metal can emerge without hindrance in countercurrent to the latter and without crossing it.

The principal objects of the invention are to provide an improvement in the known molds of the last named kind for centrifugal casting and to provide means for more advantageously carrying out the whole of the working process, which latter is known per se, the said process being also further facilitated by a hereinafter described improvement of the casting molds with regard to the material of which they are made.

The molding machine forming the subject of the invention is intended, for the purpose of attaining the maximum economy in working, to render possible a continuous working with the

highest possible rate of succession of the individual casting operations. For this reason the molds described and illustrated can and must, in addition to the construction herein shown, be provided with means known per se for cooling the molds during the casting operation. The said cooling may be effected according to choice by the aid of pressure air or pressure water.

Practice has shown that with such cooling of the molds a rapid succession of the casting operations can be attained, but this is only so attained at the cost of the lasting properties of the molds manufactured as was hitherto the case of cast iron, steel or copper, with or without insertions, consisting of interchangeably arranged plates of a nature particularly resistant to the action of the heat of the molten material which is poured into the molds. As a result of the alternate strong heating and cooling action by means of air or water, cracks readily occur in molds without insertions, whilst in molds having insertions which are more resistant to this action, the drawback arises that the said insertions expand to too great an extent and, in certain circumstances, the body of the mold, i. e., the support of the said insertions, cracks.

According to the invention, by the employment of a manufacturing material of a particular kind, a mold is provided which is particularly suitable for continuous working with the mold machine under consideration. It has been discovered that so-called heat-resistant steel of particular composition meets all the requirements hereinbefore set forth for a manufacturing material for the molds under consideration.

It is to be understood that the heat-resistant steel must be particularly adapted for the present particular application in such manner that it is able to withstand the suddenly occurring strong heating when the molten metal is poured into the mold and the strong cooling by means of pressure air or pressure water following thereupon. In order to impart to it particularly great resisting properties it may be employed not only in the cast condition, but also rolled, forged or hardened. It is also possible with water or air cooled molds, the bodies of which consist of other materials such as cast iron, to employ instead of inner mold walls or insertions consisting of copper plates or the like, plates made of the new material.

A preferred constructional form according to the invention is illustrated by way of example in the accompanying drawings, in which:

Fig. 1 is a vertical section of a molding machine

constructed according to the invention, taken on line 1—1 of Fig. 2.

Fig. 2 is a plan of the molding machine, Fig. 3 is an end elevation corresponding to Fig. 1, and

Fig. 4 shows one of the molds illustrated in Fig. 1 to a larger scale.

Referring to the drawings the reference numeral 1 denotes a shaft which is mounted in bearings 2 provided on a base 3 and is driven by means of a pulley 4 and a belt 5. On the shaft 1 centrifugal casting molds are arranged at the right and left hand sides, the said molds being carried on mold supporting members 6. The said mold supporting members 6 are fixed on the ends 10 of the shaft 1 and each carry a member 7 constituting the base portion of the mold, the cover 8 of which is detachably connected in a manner known per se by means of clamping members (not shown on the drawings) with the said base portions.

The cover 8 of the mold is provided with a central opening into which an inlet member 9 is fitted which is rotatably mounted and driven in the manner hereinafter described. The inlet member 9 is provided with a bore and is conically enlarged towards one end. Into the bore of the said inlet member 9 the nozzle of a pouring head 10 projects, by means of which the molten metal 10 which is to be fed into the mold is introduced 20 through the inlet member in a particular manner for carrying out the process above referred to, as is more closely described hereinafter.

The inlet member 9 is driven through the medium of a shaft 11, a pulley 12 and a belt 13 which are in turn driven by a pulley 14 provided on the shaft 1. The shaft 11 is journaled in hangers 15 which are fixed to supporting members 16 which on their part are fixed at the bottom to the frame 3 and held in position at the top by means of transverse connecting members 17. The inlet member 9 itself is mounted so as to be easily rotatable in suitable bearings 18 and is constructed so as to form a chain wheel 19 at its outer end, around which a driving chain 20, indicated by dotted lines in Figs. 1 and 3, passes, the said chain also passing around a chain wheel 21 mounted on a shaft 22 which is driven by the shaft 11.

For the purpose of protection against molten metal which might spurt from the molds, protecting covers 24 are provided. The bearings 18 for the inlet member 9 and the bearings 23 for the shafts 22 are fixed to the said protecting covers 24 which latter are provided with reinforcing rings 25 which surround the centrifugal casting molds 7, 8, the said protecting covers being so arranged that they can be swung on one side as indicated in dotted lines in Fig. 2, when it is necessary to dismantle or reassemble the molds 7, 8. This swinging movement of the covers 24 is rendered possible by mounting them through the medium of bearings 27 so as to be capable of turning about vertical axles or rods 26 (Figs. 2 and 3). The rods 26 are mounted in bearing blocks 28 which are screwed on to the walls 16 of the frame. Each protecting cover 24 is secured in the working position by means of a projection 29 (Figs. 2 and 3) which rests on the bearing block 31 and is provided with an extension 30 serving as a handle for swinging open the cover 24. The projection 29 is provided with a housing 32 in the interior of which a compression spring 33 is arranged, which is adapted to press a pin 33 into a recess provided in the bearing block 31.

The pin 33 must be pulled upwards before the protecting cover 24 is swung open. The shaft 11 is connected in the working position with the shafts 22 on each side by means of a simple claw coupling (Fig. 1). When the protecting covers 24 are swung open the couplings disengage automatically. The chain drive for operating the inlet member 9 as illustrated in Fig. 1 is surrounded by a protecting case 34 of sheet metal. The said case has been omitted in Figs. 2 and 3 and moreover in Fig. 3 the chain wheel 21 has not been completely illustrated but has only been indicated diagrammatically in order that the hanger 15 located behind it should be visible.

As can readily be seen from Fig. 4 the inlet member 9 is so arranged as to leave sufficient space free between it and the edges of the opening in the cover 8 of the molds as to enable the air which is displaced by the entry of the molten metal into the mold and which is strongly heated and consequently expands considerably, to escape. In order to enable the escape of the air to take place freely and in a reliable manner the inner end of the inlet member 9 is located a short distance in front of the surrounding wall of the cover 8 in order that the space between the inlet member 9 and the opening in the cover 8 shall always be kept free from the entering metal and that the air which is forced out shall find a clear path and escape in countercurrent to the metal 30 without crossing the path of the latter.

This arrangement which is known per se is elaborated in a manner known per se by arranging the inlet member 9 so that it is longitudinally movable within certain limits in order to render it 35 possible to adjust the flow of the molten metal into the mold by narrowing or broadening the space between the end of the said inlet member 9 and the inner wall of the base portion 7 of the mold, through which space the metal has to 40 pass. The said space can thus be adjusted to suit the working conditions existent at any given time, for example it may be adjusted to suit the specific gravity of the metal which is to be cast, 45 in order to ensure proper undisturbed flow of the metal into the mold.

The aforesaid adjustability of the inlet member 9 in the direction of the arrows shown in Fig. 4 is rendered possible in the constructional example under consideration by arranging the protecting cover 24 on which the inlet member is mounted through the medium of the bearing 18, so that it can be displaced within the necessary limits after fixing screws 35 have been loosened. For this purpose the bearing members 28 and 31 55 of the protecting cover 24 are provided with slots (see Fig. 2) and are guided (see also Fig. 3) by means of projections in recesses provided on the supports 36 for the bearing members, which supports are fixed to the frame 16, 3.

A further improvement of the inlet member 9 resides in the fact that the metal which is to be introduced into the mold is not led directly on to the inwardly inclined wall of the said inlet member and allowed to travel onward over the latter, but that in contradistinction to this the member 9 operates during the introduction of the molten metal in another manner as herein-after explained.

From the pouring head 10 (Figs. 1 and 3) the metal is conducted through the tubular extension or nozzle (Figs. 1 and 4) of the said pouring head downwards in an inclined direction in such manner that it strikes rapidly and in the form of a broad stream against the inner wall 75

of the rotating base portion 7 of the mold. In consequence of the impact of the stream of metal on the one hand and of the acceleration due to rotation when the stream strikes the base portion 7 of the mold on the other hand, the result is attained that the molten metal only spreads over the inner wall of the said base portion 7. The inlet member 9 serves principally to prevent the metal which is introduced in a broad stream from being thrown back on to the cover 8 upon striking upon the inner wall 7 of the mold. If this latter contingency were allowed to arise the result would be that the path of the air along the cover 8 to the space between the inlet member and the said cover would be blocked. This, however, is effectually prevented by the projecting edge of the inlet member. Any jets of metal which may be thrown back when the stream of metal strikes the inner side of the base portion 7 are caught by the inlet member 9 and passed back into the stream of metal. If the entering stream of metal is thicker than the passage for the latter between the edge of the inlet member 9 and the wall of the base portion 7 of the mold, the inlet member 9 then operates in the first place as a collecting vessel for the accumulating metal whilst serving at the same time as a funnel for introducing the metal into the mold.

30 I claim:

1. In a molding machine of the kind set forth for the centrifugal casting of annular bodies, the subcombination of: a frame; molds mounted on said frame; protecting covers arranged on said frame and surrounding said molds; inlet members associated with said molds; bearings for

said inlet members arranged on said protecting covers; and supporting members on said protecting covers displaceable in slots in said frame in such manner that the position of said inlet members with regard to said protecting covers can be adjusted axially to suit different conditions.

2. In a mold machine of the kind referred to, the subcombination of: a frame; molds mounted on said frame; protecting covers for said molds, said covers being carried by said frame and surrounding said molds; inlet members for said molds rotatably carried by said covers; means for rotating said molds; inlet members for said molds rotatably carried by said protecting covers; means for rotating said members, said means including rotatable shafts carried by said covers; means operable by said mold-rotating means for rotating said shafts and chain mechanism transmitting the motion of said shafts to said inlet members.

3. In a molding machine of the kind referred to, the subcombination of: a frame; molds mounted on said frame; vertical axles on said frame; protecting covers for said molds swingably mounted on said axles; rotatable inlet members for said molds carried by said protecting covers; means for rotating said molds; means for rotating said members, said means including rotatable shafts journaled in said covers, said shafts being operatively connected to said inlet members; means operable by said mold-rotating means, for rotating said shafts; and claw couplings between said shafts and said last-mentioned means adapted to be disengaged when said protecting covers are swung outwardly.
